UNITED STATES PATENT OFFICE.

JAMES H. GILROY, OF NEWARK, NEW JERSEY.

UMBRELLA RING AND MARKER.

1,279,327.

Specification of Letters Patent. Patented Sept. 17, 1918.

Application filed December 31, 1917. Serial No. 209,703.

To all whom it may concern:

Be it known that I, JAMES H. GILROY, a citizen of the United States, and a resident of Newark, in the county of Essex and State of New Jersey, have invented a new and Improved Umbrella Ring and Marker, of which the following is a full, clear, and exact description.

This invention relates to an attachment 10 for an umbrella for the purpose of holding the tips of the ribs close to the handle rod when the umbrella is closed, and for the purpose of designating the owner of the umbrella.

15 The invention has for its general objects to provide a device of this character which is of comparatively simple and inexpensive construction, reliable and efficient in use, and so designed that when once applied to an umbrella it cannot be detached, and consequently the owner's name will be always carried on the umbrella.

20 A more specific object of the invention is the provision of a clamping ring and marker 25 which is in the form of a spring band having overlapping ends which are movably locked together so that the band can be expanded so as to be movable on and off the tips of the umbrella ribs from and to the 30 handle, the band being normally under a spring tension tending to contract it and thereby hold the umbrella ribs close together.

Still another object of the invention is the 35 provision of a novel arrangement of locking means for preventing the opening of the band far enough to detach it from the umbrella, such locking means forming finger-holds for enabling the band to be 40 manipulated for adjusting it on and off the ribs.

With such objects in view, and others which will appear as the description proceeds, the invention comprises various novel 45 features of construction and arrangement of parts which will be set forth with particularity in the following description and claims appended hereto.

In the accompanying drawing, which 50 illustrates one embodiment of the invention and wherein similar characters of reference indicate corresponding parts in all the views,

55 Figure 1 is a fragmentary view of an umbrella with the ring and marker applied thereto;

Fig. 2 is a perspective view of the ring and marker detached;

Fig. 3 is a horizontal sectional view thereof;

Fig. 4 is an enlarged sectional view on the 60 line 4—4, Fig. 3.

Fig. 5 is a plan view of the device fully opened or spread out flat and with the locking bar detached; and

Fig. 6 is a plan view of the blank from 65 which the device is made.

Referring to the drawing, 1 designates a handle of an umbrella, 2 the ribs and 3 the covering, and A designates the ring and marking attachment.

70 The attachment A comprises a band 4 of spring metal of such length that the ends 5 and 6 overlap to a considerable length, as shown in Fig. 3, the normal diameter of the band or ring being such as to hold the ribs 75 of the umbrella close against the handle rod. The ring can be spread open far enough to permit it to be engaged around the handle 1, and when the ring or band is released it will contract into snug fitting relation to the handle. To move the ring on and off the handle for engagement with or disengagement from the ribs 2 suitable projecting members are attached to the ends of the spring strip from which the ring or 85 band is made, so that these members can be engaged by the thumb and forefinger and drawn together to thereby increase the diameter of the ring, and when the ring is in the proper position of adjustment the members 90 are released so that the spring will contract and perform its proper holding function. In the present instance one end is formed with an enlargement 7 folded on the line 8, and then the enlargement is folded on the 95 line 9 so as to produce an outstanding flange 10, Figs. 2, 3 and 5. The opposite end of the blank is provided with lugs 11 which are doubled on the lines 12, and then the lugs are bent on the line 13 so as to stand 100 parallel with each other and straddle the opposite end of the band when the same is curled. The ears 14 thus formed can be gripped by the thumb or forefinger while the member 10 is gripped by the forefinger 105 or thumb, and by drawing the members toward each other the spring is expanded. The ears 14 have apertures 15 through which passes a locking bar 16 having knobs or heads 17 on the ends which retain the 110 locking bar in place. This locking bar is applied after the device is attached to an

umbrella, and when the locking bar is once applied the attached device cannot be removed, since the lugs 14 and the bar cooperate to prevent the projection, lug or gripping piece 10 from passing between them, the bar 16 being swaged or upset so as to prevent the removal of the nut 17.

The outside of the band may be used for marking purposes, and the owner's name and address will be suitably applied thereto.

In the present instance a marking card 18 with the owner's name and address thereon is fastened to the outer surface of the band in any suitable manner, as, for instance, by small ears 19 on the longitudinal edges of the band and bent inwardly toward each other to form retainers, and over the card 18 may be a strip of celluloid 20 for protection. The strip and card may be the full length of the band or extend only part of the length thereof. On one end of the band is a bent-back flange 21 under which the ends of a long card and protective strip are engaged.

From the foregoing description taken in connection with the accompanying drawing, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative and that such changes may be made when desired as fall within the scope of the appended claims.

Having thus described my invention, I claim as new and desire to secure by Letters

Patent:

1. An attachment of the class described

comprising a spring band having overlapping ends, a pair of lugs on one end and between which the other end slidably engages, a member on the other end movable toward the lugs and of such size as to prevent its passage between the lugs, and means on the lugs for holding the ends together. 45

2. A device of the class described comprising a ring having overlapping ends, a finger-grip on the underlapping extremity of the ring, and a finger-grip on the extremity of the overlapping extremity of the ring whereby the pressing of the finger-grips toward each other expands the ring. 50

3. A device of the class described comprising a band made of a spring strip having overlapping ends, a lug on one end forming a finger-grip, and a pair of lugs on the other end forming a finger-grip, said grip pieces being so related that they can be gripped respectively by the thumb and first finger of one hand and drawn together for expanding the band. 60

4. A device of the class described comprising a band made of a spring strip having overlapping ends, a lug on one end forming a finger-grip, a pair of lugs on the other end forming a finger-grip, and a locking bar attached to the said pair of lugs to form a stop to limit the opening of the device. 65

5. An umbrella attachment of the class described comprising a spring metal strip bent into a band having overlapping ends free to slide one on the other, a pair of lugs projecting outwardly from the underlying end, a lug projecting outwardly from the outer end of the strip, a locking bar passing through the first-mentioned lugs and having headed extremities lying outwardly of the latter. 75

JAMES H. GILROY.
